UNITED STATES PATENT OFFICE.

GUY DINCOGNITO, OF CHICAGO, ILLINOIS.

WIRE JOINT.

Application filed January 6, 1923. Serial No. 610,982.

To all whom it may concern:

Be it known that I, GUY DINCOGNITO, a citizen of the United States, and a resident of the city of Chicago, county of Cook, and 5 State of Illinois, have invented certain new and useful Improvements in Wire Joints, of which the following is a specification.

This invention relates to wire joints and has for its object the provision of a construction of this character particularly adapted for use in wire lamp-shade frames, which joints will be inconspicuous and attractive in appearance, strong and durable, and economical of manufacture.

15 Other objects will appear hereinafter.

The invention consists in the combinations and arrangements of parts hereinafter described and claimed.

The invention will be best understood by 20 reference to the accompanying drawings forming a part of this specification, and in which,

Figure 1 is an elevational view of a portion of a wire lamp-shade frame showing 25 my invention applied thereto;

Fig. 2 is a view partly in section on the line 2—2 of Fig. 1 showing the joints in position to have a binding agent applied thereto; and

30 Fig. 3 is a view similar to Fig. 2, showing the completed joints.

The present invention is an improvement on the construction shown and described in my companion application filed January 6, 35 1923, Serial No. 610,981, and contemplates wire joints of a type particularly adapted for use in wire lamp-shade frames, in which the various wires for the frame are angularly bent in various ways to impart the de- 40 sired shape thereto.

A portion of a wire lamp-shade frame is illustrated in Fig. 1, in which 5 represents a member, which for the purposes of this description I will designate a frame wire.

45 A plurality of members 6 which I will refer to as web wires, each has one end connected to the frame wire 5 by means of a reduced end, forming a type of joint shown and described in my application above referred to, 50 the opposite ends of the wires 6 being connected to a frame wire (not shown) similar to the wire 5.

As shown in Fig. 2, when used in connection with a lamp-shade frame, each of the 55 members 6 is preferably angularly bent inwardly at any desirable point as shown at 7,

and on the outer side of said bend there is provided a reduced portion preferably in the form of a notch 8. Disposed at an angle to the wire 6 and adapted to be placed within the notch 8 is a member 9 which I will refer to as a brace wire. When the wire 6 is bent and provided with the notch 8, and the wire 9 placed in said notch, as shown in Fig. 2, it is apparent that when a binding agent is applied to the parts, a joint is provided on the outer side of the bent portion as shown at 10 in Fig. 3, which is scarcely noticeable.

The wire 6 may also be outwardly bent as 70 shown at 11 in Fig. 2, such wire having a reduced portion forming a notch 12 on the inner side of the bend, the notch in this instance preferably being undercut and almost closed. Disposed at an angle to the wire 6 75 is a brace wire 13, said brace wire being receiveable in the notch 12 as shown, it being apparent in this construction that by reason of the shape of the notch, the brace wire 13 is held therein without otherwise 80 securing the same, though it is preferred to apply a binding agent such as solder to the parts which provides a joint of the character shown at 14 in Fig. 3.

By the above described arrangement it is 85 apparent that the joints thus formed are practically unnoticeable, thereby doing away with the objectionable and unattractive joints which would be produced if the wires 6 were not altered in the manner de- 90 scribed.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of 100 the appended claims.

Having described my invention what I claim as new and desire to secure by Letters Patent, is:

1. A joint of the character described comprising a member having a bend therein, said member being reduced at the inner side of said bend to form an undercut notch, and another member disposed at an angle to said first member and mounted in said notch. 105

2. A joint of the character described comprising a member having an angularly bent

portion therein, said bent portion being reduced at the outside of said angular portion to form a notch in its outside surface, another member disposed in said notch, and means for binding together the joint thus formed.

3. A joint of the character described comprising a member having a bend therein, said member being reduced at the inner side of said bend, another member disposed at an angle thereto and engaging said reduced portion, and means for binding together the joint thus formed.

4. A joint of the character described comprising a member having a bend therein, said member being reduced at the inner side of said bend to form an undercut notch, another member disposed at an angle to said first member and mounted in said notch, and means for binding together the joint thus formed.

5. A fabric including a frame wire, web wires connected to said frame wire and at

an angle thereto, each of said wires being bent inwardly and then outwardly, said wire being reduced adjacent the outer side of the inwardly bent portion and reduced on the inner side of the outwardly bent portion, brace wires engaging said reduced portions, and means for binding together the joints thus formed.

6. A joint of the character described comprising a member having an angular bend therein, said member being reduced at the inner side of said bend to form an undercut notch having curved walls, and another member disposed at an angle to said first member, said other member being round in cross-section and mounted in said notch.

In testimony whereof I have signed my name to this specification in the presence of two subscribing witnesses.

GUY DINCOPNITO.
